[57] CLAIM

The ornamental design for a tableware container, as shown and described.

DESCRIPTION

FIG. 1 is a top perspective view of a tableware container showing may design;

FIG. 2 is a front elevational view thereof, the rear view, the left view, and the right view being identical to the front elevational view;

FIG. 3 is a top plan view thereof;

FIG. 4 is a bottom plan view thereof; and,

FIG. 5 is a perspective view illustrating the tableware container with some tableware received therein, the tableware being shown by phantom lines for illustrative purpose only.
